WILLIAM A. CHRYSST, OF DAYTON, OHIO, ASSIGNOR TO DELCO-REMY CORPORATION, OF DAYTON, OHIO, A CORPORATION OF DELAWARE

IGNITION TIMER

Application filed January 13, 1928. Serial No. 246,640

This invention relates to ignition apparatus for internal combustion engines, and more particularly to the control of ignition timing in response to variations in engine speed and to variations in engine load.

One object of the present invention is to provide for the control of ignition timing by means cooperating with a metal bellows of conventional construction, said means and bellows being adapted to be located within the timer housing. In carrying out this object of the invention, I provide a cam carrying shaft which is journaled upon a portion of the timer driving shaft so that it may be rotated relative thereto, and I connect the shafts by a mechanism which can be confined within the timer housing and which includes the conventional metal bellows providing a pressure chamber which is connected with the intake passage of the engine. The bellows is located preferably parallel to the timer driving shaft and along one side thereof and controls a member which moves along the shaft and is so connected with the driving shaft and cam carrying shaft as to change the angular relation between these shafts in response to the expanding or collapsing of the bellows.

Further objects and advantages of the present invention will be apparent from the following description, reference being had to the accompanying drawings, wherein a preferred form of embodiment of the present invention is clearly shown.

In the drawings:

Fig. 1 is in part a vertical sectional view of an ignition timer embodying the present invention and in part a diagram showing the manner of connecting the suction chamber of the ignition timer with the engine intake passage.

Fig. 2 is a plan view of the timer with the distributor head removed.

Fig. 3 is a fragmentary sectional view of certain parts shown in Fig. 1 but this figure shows the parts in different positions.

Fig. 4 is a sectional view on the line 4—4 of Fig. 1.

Fig. 5 is a fragmentary view looking in the direction of the arrow 5 of Fig. 1.

The ignition timer housing 20 is provided with a tubular shank 21 which provides a bearing for the timer driving shaft 22 which is provided with a C-washer 23 resting upon a round washer 24 which in turn rests upon the bottom of a recess 25 provided in a boss 26 of the timer housing 20. Thus the shaft 22 is rotatably supported by the housing and is prevented from moving downwardly through the shank 21. The shaft 22 provides bearings for an intermediate shaft 27 and for a cam carrying shaft 28 providing a timer cam 29. The shaft 27 is supported vertically by resting upon the collar 23 and the shaft 28 is supported vertically by resting upon a shoulder 30 provided by the shaft 22. The shaft 28 supports and drives a rotor block 31 carrying a conducting segment 32 which cooperates with distributor posts 33 carried by a distributor head 34 which is clamped upon the housing 20 in any suitable manner, not shown. The segment 32 is connected with a leaf spring conductor 35 carrying a button 36 which engages a button 37 carried by the center metallic terminal receiving socket 38.

The cam 29 provided with the shaft cooperates with a rubbing block 40 of the circuit interrupter lever 41 in order to separate a movable contact 42 carried by the lever 41 from a stationary contact 43 attached to a bracket 44 adjustably secured to a breaker plate 45 by screw 46 passing through an arculate slot 47. The lever 41 and the bracket 44 are concentrically pivoted around a pivot stud 48 attached to the plate 45. A leaf spring conductor 49 conducts current from the terminal bracket 50 to the lever 41 and also urges the lever toward the cam 29. The terminal bracket 50 is insulatingly supported by the plate 45 and is connected with a terminal screw 51 insulated from the housing 20.

A wire 52 connects the bracket 50 with the insulated foil of a condenser located within a case 53 to which one of the foils is grounded the case being grounded to the ignition timer through the bracket 54 soldered to the case 53 and fastened by a screw 55 to the plate 45.

The means for connecting the intermediate shaft 27 with the cam carrying shaft 28 comprises a weight supporting plate 60 fas-

tened at the upper end of the shaft 27 and supporting a plurality of weights 61 which are pivoted around the studs 62 attached to the weight plate. Each weight 61 is provided with an arm 63 for engaging an arm provided by plate 64 attached to the lower end of the shaft 28. As the weights 61 move away from the shaft 28 in response to increase of speed, the arms 63 will cooperate with the plate 64 so as to rotate the shaft 28 clockwise relative to the shaft 27 and thus advance the timing of the ignition, the normal direction of rotation of the cam 29 being clockwise. As the speed of the shaft 27 decreases, the plate 64 will be moved counterclockwise and the weights 61 will be moved toward the shaft 27 by springs 65 each connected at one end with a stud 62 and at the other end with a stud 66 attached to the plate 64.

The means for connecting the shafts 22 and 27 and for varying their angular relation in response to variations in pressure in the engine intake passage comprises a washer 70 which is provided with tangs or lugs 71 extending radially through oblique slots 72 in the sleeve 27 and into longitudinally slots 73 which are provided in the shaft 22 and extend from the C-washer 23 through the shoulder 30. Obviously when the washer 70 is moved along the shaft 22, the angular relation between the shafts 22 and 27 will be varied. The washer 70 is moved vertically as viewed in the drawings, by a plate 74 which is provided with arms 75 located on either side of the shaft 27 and provided with longitudinal slots for receiving edge portions of the washer 70. The plate 74 is attached to the bottom of a metal bellows 76, the top of which is secured to a horizontal wall 77 extending from a cover plate 78 which encloses an opening formed in one side of the housing 20 and is secured to the housing by screws 79. The plate 74 is guided in its vertical movements relative to the wall 77 by telescopically engaging sleeve members 80 and 81, the former being integral with a plug 82 which is screwed into the threaded opening in the plate 74, and the latter being integral with the horizontal wall 77. These sleeves retain a spring 83 which yieldingly urges the plate 74 downwardly into engagement with a stop plate 84 which is attached by screws 85 to the cover 78. The suction chamber 90 provided within the bellows 76 is connected by a hole 91 with the interior of the sleeve 83 and the sleeve 83 is connected by a passage 92 in the cover 78 with an elbow pipe 93. Fig. 1 diagrammatically shows a pipe 94 connecting the elbow 93 with a passage 95 which is provided by a carburetor 96 attached to an engine intake manifold 97. The butterfly-throttle valve 98 of the carburetor is supported by a shaft 99 operated by

a lever 100 and a link 101. The passage 95 is below the edge of the valve 98 when the valve is in idling position.

The suction in the engine intake between the engine and the throttle will be greatest when the engine speed is greatest and the throttle is partly closed corresponding to conditions driving an automobile at a relatively high speed over a relatively level road. The increase in suction or sub-atmospheric pressure in the intake 97 will result in the more or less collapsing of the bellows 76 as viewed in Fig. 3. The washer 70 will therefore move upwardly to cause the shaft 27 to rotate in a clockwise direction relative to the shaft 22. Therefore the cam 29 will be rotated in a clockwise direction relative to the shaft 22 and the timing of the ignition will be advanced. If the load on the engine should increase requiring the throttle 98 to be opened the suction in the intake 97 will decrease and the spring 83 will be permitted to expand to cause the plate 74 to move away from the wall 77, thereby moving the washer 70 downwardly to rotate the shaft 27 counterclockwise relative to the shaft 22 and to retard the timing of the ignition.

The housing 20 provides a horizontal ledge 110 providing a bearing 111 for the shaft 27. The ledge 110 provides a pocket 112 for receiving a pad 113 of fibrous material which may be soaked with oil admitted through a pipe 114 and dispensed through a passage 115. Some of this oil will find its way down the shaft through the grooves 72 to the outer surface of the shaft 22 and in the grooves 73 in order that the contacting surfaces between the shafts 22 and 27 may be lubricated and also the surfaces of the grooves which are engaged by the tangs 71 of the washer 70.

In assembling the apparatus the washer 70 is first placed within the housing and is located between the shank 21 and the ledge 110 and in alignment with the bearings provided by these parts. Then the shaft 22 is moved upwardly through the shank 21 and its grooves 73 are positioned so as to receive the tangs 71 of the washer 70. The shaft 22 is moved upwardly through the bearing 111 until the groove 23^a is located above the boss 26. Then the C-washer 23 is placed in the groove 23^a and the shaft 22 is lowered until the washer 23 rests upon the washer 24. Then the shaft 27 is moved downwardly along the shaft 22 and is passed through the bearing 111 and is so positioned that its grooves 72 will receive the tangs 71 of the washer 70. Then the cam carrying shaft 28 is assembled on the shaft 22 and the springs 65 are connected with the studs 62 and 66. Following this the breaker plate with the parts attached thereto is mounted within the timer housing 20. Then the distributor rotor and the head are assembled in the usual manner. The cover 78 carrying the mechanism for shifting the

collar 70 is attached to the housing, the cover being moved first so that the slotted arm 75 will receive the washer 70.

Since the upward movement of the washer 70 tends to move the shaft 27 upwardly due to the coaction of the tangs 71 and the walls of the oblique slots 72, the cam carrying shaft 28 is provided with a collar 116 for engaging the underside of the interrupter supporting plate 45. If the shaft 27 tends to move upwardly it will be resisted by the plate 64 which rests upon the weight plate 60 and upward movement of the plate 64 will be resisted by the engagement of the collar 116 with the plate 45.

The maintenance of the apparatus in operative condition is facilitated by a construction which permits removal of the suction operated mechanism for shifting the collar 70 without requiring other parts of the timer to be disassembled. After disconnecting the pipe 94 from the plate 78 and after removing the screws 79, the plate 78 and mechanism supported thereby for shifting the collar 70 may be removed as a unit for repairs or re-placements without disturbing the speed responsive mechanism for connecting the cam with the drive shaft of the timer. After removing the distributor head 34 and the interrupter carried by the breaker plate 45, the cam carrying shaft 28, the intermediate shaft 27, and the speed responsive means connecting the shafts 28 and 27 may be removed as a unitary assembly without disturbing the other mechanism for shifting the collar 70.

While the form of embodiment of the present invention as herein disclosed, constitutes a preferred form, it is to be understood that other forms might be adopted, all coming within the scope of the claims which follow.

What is claimed is as follows:

1. Ignition apparatus for internal combustion engines comprising, in combination, an interrupter, a drive shaft, a cam for operating the interrupter journaled upon the drive shaft, a driven shaft connected with the cam, and means for connecting the shafts and for varying the angular relation between them in response to variations in engine intake suction and including a suction chamber provided by a metal bellows, one end wall of which is movable longitudinally of the shaft, a collar movable along the shafts and so connected with them as to change their angular relation as the collar is moved, and means transmitting motion from the movable end wall of the bellows to the collar.

2. Ignition apparatus according to claim 1 in which the apparatus has a housing provided with an opening in a wall thereof, and in which the cover for the opening supports the bellows.

3. Ignition apparatus according to claim 1 in which the apparatus has a housing provided with an opening in a wall thereof, and

in which a unitary sub-assembly covers the opening and includes the bellows and the means for transmitting motion from the movable end wall of the bellows to the collar, the sub-assembly being removable from the housing while the collar remains assembled with the shafts.

4. Ignition apparatus for internal combustion engines comprising, in combination, an interrupter, a cam for operating the interrupter, a drive shaft, a driven shaft connected with the cam, said cam and driven shaft being journaled upon said drive shaft, a collar movable along the shafts and so connected with them that one will be rotated relative to the other as the collar is moved, means responsive to variations in engine intake suction for moving the collar and comprising a suction chamber provided by a metal bellows located substantially parallel to the drive shaft, and a plate attached to an end wall of the bellows and connected with the collar so as to move the same along the shaft while permitting rotation of the collar.

5. Ignition apparatus for internal combustion engines comprising, in combination, an interrupter, a cam for operating the interrupter, a cam-carrying shaft, an intermediate shaft, a drive shaft providing bearings for the other shafts, a speed responsive device for connecting the intermediate and cam-carrying shafts and for changing the angular relation between them, a collar for connecting the intermediate shaft and drive shaft and having a lug extending into grooves in these shafts, one of the grooves being oblique to the axes of these shafts, whereby movement of the collar along these shafts will cause one of them to rotate relative to the other, the intermediate shaft, cam-carrying shaft and speed responsive device being removable while assembled from the apparatus leaving the collar assembled with the drive shaft, and a device responsive to variations in engine intake suction for moving the collar, said device comprising a removable plate attached to the apparatus, a metal bellows attached at one end to the plate, and a movable plate attached to the free end of the bellows and connected with the collar so as to move the same along the shaft while permitting rotation of the collar.

In testimony whereof I hereto affix my signature.
